KETCHUM, OF NORTH YAKIMA, WASHINGTON.

SHOE-FINISHING MACHINE.

1,212,724.

Specification of Letters Patent. Patented Jan. 16, 1917.

Application filed October 30, 1915. Serial No. 58,862.

To all whom it may concern:

Be it known that I, JOSEPH C. WISE, a citizen of the United States, residing at North Yakima, in the county of Yakima 5 and State of Washington, have invented a new and useful Shoe-Finishing Machine, of which the following is a specification.

The present invention appertains to shoe finishing machines, and aims to provide a 10 novel and improved appliance of that character.

One of the objects of the invention is the provision of a shoe finishing machine embodying in connection with a main frame, a 15 supplemental or secondary frame assembled with the main frame for supporting a stitcher.

With the foregoing and other objects in view which will appear as the description 20 proceeds, the invention resides in the combination and arrangement of parts and in the details of construction hereinafter described and claimed, it being understood that changes in the precise embodiment of the invention herein disclosed can be made within 25 the scope of what is claimed without departing from the spirit of the invention.

The invention is illustrated in the accompanying drawings, wherein:

30 Figure 1 is an elevation of the machine. Fig. 2 is a vertical section thereof taken on the line 2—2 of Fig. 1.

The main frame of the machine embodies upright end castings or standards 1 connected adjacent their lower ends or feet by a pair of longitudinal pipes 2 which are terminally secured to said standards, and said standards are connected between their upper and lower ends by a second pair of pipes 3 35 which have their terminals secured within inwardly projecting apertured lugs 4 of the standards. The pipes 2 and 3 provide stays to rigidly connect the standards.

The supplemental or secondary frame for 45 supporting the stitcher (not shown) embodies an upright casting or standard 5 of less height than the standards 1, and a pair of upper longitudinal pipes or tubular members 6 having certain ends secured upon the 50 upper end of the standard 5 by means of clamps 7. The other terminals of the pipes 6 fit slidably in the outstanding apertured lugs 8 of one of the standards 1, each of said

standards 1 being provided with outstanding lugs 8 opposite the respective lugs 4 and 55 set screws 9 are carried by the lugs 8 for clamping the pipes 6 in place. The lower portions of the standard 5 and the respective standard 1 are connected by a longitudinal pipe or tubular member 10 which is connected to the standards by means of clamps 11. The pipes 6—10 project in one direction 60 from the standards 5 and are applicable to either standard 1, so that the secondary frame or stand for the stitcher can be applied by reversing it, to either end of the main frame. The stitcher is supported upon the pipes 6, and is fastened thereto in any suitable manner.

A longitudinal shaft 12 is journaled in 70 bearings 13 carried by the upper ends of the standards 1, and a second longitudinal shaft 14 is journaled in bearings 15 with which the standards 1 are provided below the bearings 13. The bearings are preferably provided with lubricant cups 16 for lubricating 75 the shafts.

Rearwardly projecting brackets 17 are attached to the main frame adjacent the ends thereof, and carry a longitudinal shelf 17' 80 adjacent the upper ends and in rear of the standards. The said shelf can be used for holding shoes, implements, and other articles. Black and tan ink pots 18 are attached to the forward edge of the shelf 17' 85 where they can be reached easily.

In order to operate the shafts 12—14 an incased electric motor 19 is mounted upon a longitudinal shelf 20 disposed between the pipes 2 and 3, and having one end attached 90 to one standard 1, while the other end of the shelf 20 is supported by means of hangers 21 having their upper ends attached to couplings or sleeves 22 upon the pipes 3 between their ends. The armature shaft 23 95 of the electric motor 19 has secured thereon a pulley wheel 24 connected by an endless belt 25 with a pulley wheel 26 upon the shaft 14, and a second pulley wheel 27 upon the shaft 14 is connected by an endless belt 100 28 with a pulley wheel 29 upon the upper shaft 12. Thus, when the electric motor is operated, both shafts are rotated. An exhaust fan 30 is also mounted upon the shelf 105 20 and has the armature shaft 23 connected thereto, said fan having a suction conduit

2
 31 connected to a hood 32 disposed below and in rear of the shaft 14. A breasting wheel 33 is secured upon one protruding end of the shaft 14 remote from the stitcher stand, and is partially inclosed by a hood 34 connected by a pipe 35 with the conduit 31, whereby the suction created by the fan 30 extends from the conduit 31 through the pipe 35 to the hood 34. This will draw in 10 the dust given off from the wheel 33. A pulley wheel 36 is keyed to the other protruding end of the shaft 14 and is adapted to be connected to the stitcher carried by the stitcher stand.

15 An emery wheel 37 is secured upon the protruding end of the shaft 12 above the pulley wheel 36. The shaft 12 has secured thereon between the standards 1, a black bristle brush 38, a black wax finishing roll 20 39, a tan wax finishing roll 40, a combined bottom leveler and edge setter 41, and a tan bristle brush 42, said rolls and brushes being operated by the upper shaft 12. The lower shaft 14 has secured thereon above the 25 hood 32, a sand scouring roll 43, a bottom sand scouring roll 44, and a breasting wheel or scouring roll 45. The dust given off by the rolls 43, 44 and 45 is sucked into the hood 32 and is drawn to the fan 30 by the 30 conduit 31. The dust can be discharged to the point desired from the fan.

Disposed loosely upon each exposed portion of each shaft, is a sleeve 46, said sleeve inclosing those portions of the shafts which 35 would be otherwise exposed. The sleeves 46 can rotate with the shafts, but should the sleeve of the operator or other object engage one of the sleeves 46, it stops rotating, to prevent the fabric or other object 40 being entangled with the shaft.

A key 62 is hung by a chain 63 from the forward pipe 3, whereby the key 62 is always handy for use in taking care of parts of the machine.

Having thus described the invention, what 45 is claimed as new is:—

1. A shoe finishing machine embodying a main frame composed of end standards and longitudinal stays connecting them, a stitcher stand embodying a standard and 50 horizontal members attached thereto and slidably engaging one of the standards above the main frame, and means carried by said standard of the main frame for clamping 55 said members.

2. A shoe finishing machine embodying a main frame composed of end standards and longitudinal stays connecting them, and a reversible stitcher stand embodying a 60 standard and horizontal members attached thereto and projecting in one direction therefrom, each of the standards of the main frame having portions for receiving and clamping said members of the stitcher stand.

3. A shoe finishing machine embodying a main frame composed of end standards and a pair of longitudinal stays connecting them between their upper and lower ends, a longitudinal shaft journaled in the standards above said stays and having shoe finishing means thereon, a shelf attached at one end to one standard below said stays, hangers connecting the other end of said shelf and said stays, a motor upon said shelf having a shaft operatively connected with the aforesaid shaft, an exhaust fan mounted upon said shelf and connected to the motor shaft, and a hood coöperable with said shoe finishing means and having a conduit connected to said fan.

In testimony that I claim the foregoing as my own I have hereto affixed my signature in the presence of two witnesses.

JOSEPH C. WISE.
